BEER COOLER

August L. Voight, Lakewood, Ohio

Application February 27, 1934, Serial No. 713,143

11 Claims.

(Cl. 225—9)

This invention relates to a cooling apparatus for use in the dispensing of beverages such as draft beer and the like.

An object of the invention is to provide an apparatus of the character specified which enables the drawing of properly cooled draft beer which will at all times have the desired "life" and taste.

Another object is to provide an apparatus of this character which enables a maximum amount of properly cooled draft beer to be withdrawn in a given period of time whereby increased demand, such as occurs during rush hours, will be taken care of.

Another object is to provide an apparatus of this character in which the beer may remain for considerable periods of time, such as over night, without going flat or otherwise losing its desirable properties.

A further object is to provide an apparatus, as above mentioned, which is so constructed as to facilitate the cleansing of the apparatus and the preparation of the same for the actual dispensing of draft beer.

A still further object is to provide an apparatus of this character which is economical in use in that it is substantially unnecessary to withdraw and waste any of the beer in order to get the same into the proper condition for sale.

An additional object is to provide an apparatus of this character which is simple in construction and economical to manufacture.

Further and additional objects and advantages will appear hereinafter during the following detailed description of two embodiments of the invention which are illustrated in the accompanying drawings, wherein

Figure 1 is a vertical transverse sectional view through an apparatus representing one embodiment of the invention.

Fig. 2 is a sectional view taken substantially on line 2—2 of Fig. 1, looking in the direction of the arrows.

Fig. 3 is a fragmentary sectional view illustrating a slightly modified form of one of the structural details shown in Fig. 1.

Fig. 4 is a transverse vertical sectional view of a modified form of apparatus embodying the invention, certain portions being shown in elevation.

Fig. 5 is a top plan view of the embodiment shown in Fig. 4, and

Fig. 6 is a detail view of an attachment which may be used in the apparatus.

Referring to Fig. 1 of the drawings, the apparatus is shown as positioned within an ice or cool-

ing container 10 which may be of any preferred construction and suitably insulated, as is well understood in the art. As an example of the type of ice or cooling chamber that may be employed, reference is made to the usual ice chamber provided in service and other bars and through which ordinarily the conventional beer coils extend and are connected to taps conveniently and accessibly located. It will be understood that the container 10 is filled with cracked ice and that the apparatus embodying the invention, as disclosed in Fig. 1, is substantially immersed in this cracked ice.

The apparatus comprises a beer receptacle or cooler 11, which, as illustrated, is substantially cylindrical in shape and is preferably formed of a casting of a suitable metal having the desired thermal characteristics, light weight, and which will not affect the taste or quality of the beer, as for example an aluminum casting. The receptacle 11 is externally threaded adjacent its open end, whereby it can be closed by means of a suitable closure cap 12 screwed thereon and having external ribs 13 or other means, which may be used as a handle to facilitate the application and removal of the closure cap to and from the receptacle. A suitable gasket 14 will, of course, be interposed between the end of the receptacle and the closure cap.

The receptacle adjacent its closed or upper end 30 is provided with a laterally offset extension 15 and, since the receptacle 11 is preferably arranged in the container 10 at an angle, such as indicated in Fig. 1, it will be seen that the offset portion 15 provides a gas chamber 16 of substantial size above the maximum level of the beer line, as will later be referred to.

The receptacle 11, as already stated, is arranged in the container 10 at an upwardly inclined angle and is supported by means of a suitable support 17 fixed within the container and having at its upper end an arcuate portion 18 which fits and engages the exterior surface of the receptacle 11. The support 17 may be formed of any suitable metal and is preferably provided with openings and constructed so as to make the same light in weight. The receptacle 11 is further held in position upon the arcuate portion 18 of the support 17 by the conduits connected thereto and by the ice in which it is immersed.

The keg which supplies the beer to the receptacle 11 and the usual pressure tank connected to the keg may be arranged in any suitable and usual place and the beer brought from the keg 55

to the receptacle by means of a conduit 19 connected to the receptacle by a suitable fitting 20.

The receptacle 11 adjacent its upper end but below the gas chamber is provided with an inlet pipe 21 secured in the opening in the receptacle to which the fitting 20 is likewise attached, such inlet pipe being curved and extending inwardly, downwardly, and then toward the wall of the receptacle, as shown in Fig. 1. The inlet pipe 21 is located on the lower side of the inclined receptacle whereby, as the beer enters the receptacle through the pipe 21, it will strike the inclined wall of the receptacle and flow down along the same, with the result that an excess 10 of foam on the beer in the receptacle is avoided.

It will be seen that as the beer flows into the inclined receptacle and down the lower wall thereof to the bottom the gases will rise toward the gas chamber 16 and, as the level of the beer 20 in the receptacle increases and reaches a level just above the inlet pipe 21, as indicated in the drawings, these gases will be compressed in the chamber 16 and will act to eliminate all foam in the beer as do the gases which are compressed 25 in the top of bottled beer, with the result that the receptacle 11 will contain only liquid beer free from a head of foam. As soon as the compressed gases in the chamber 16 attain a pressure equal to the pressure in the supply keg, the 30 incoming flow of beer will cease until there is a withdrawal of beer.

The outlets from the receptacle are located adjacent the lower end of the receptacle wherefore the beer withdrawn from the receptacle will 35 always be taken from such end when the beer is liquid and free of foam. Although any number of outlets might be provided for the receptacle, two outlets have been shown herein by way of illustration.

40 The receptacle at the points of outlet is provided with bosses 22 having suitable bores therethrough communicating with the interior of the receptacle, which bores, adjacent the outer end of the bosses, are enlarged and threaded so as 45 to receive the threaded end of suitable connecting fittings 23 in turn connected to the outlet conduits 24. The bore through one of the bosses 22 is cylindrical, while the bore through the other boss 22 is formed with a conical end 50 25 for a purpose later to be explained. The outlet conduits 24 extend to suitable taps 26 located exteriorly of the container 10 in any desired and accessible position, but below the level of the gas chamber 16.

55 A tube 27 extends centrally and longitudinally of the receptacle and is provided at its upper end and within the gas chamber 16 with an enlarged flared funnel-like portion 28, it being noted that the outer end of this funnel-like 60 portion lies adjacent to, but spaced from, the closed end of the receptacle, as indicated in Fig. 1. The lower end of the tube 27 has a hollow spherical portion 29 provided with openings 30 and with laterally extending bosses 31 through 65 which bores are provided. One of the bosses 31 is exteriorly threaded, wherefore a swivel connecting nut 32 can be screwed thereon, such nut being carried by a short cylindrical pipe 33, the outer end of which extends into the cylindrical 70 bore in one of the bosses 22 and thus connects the tube 27 with one of the outlet conduits 24. The bore through the other boss 31 is conical in shape adjacent its outer end and receives the conical end of a short pipe 34, the other conical 75 end of such pipe being received in the comple-

mentary conical portion 25 of the bore through the other boss 22, whereby the second outlet conduit is connected to the tube 27.

The tube 27 carries adjacent its upper end and approximately at the inlet level a disk 27^b which may be integrally formed with the tube or a separate piece secured thereto. The disk 27^b is for the purpose of deadening the foam on the rising beer in the receptacle.

The upper end of the receptacle 11 has a pair 10 of openings formed therein to one of which a suitable automatic blow-off valve 35 is connected and to the other of which a pet-cock may be connected, if desired, or preferably a pipe 36 is connected and leads to a pet-cock 37 located externally of the container 10 above the level of the inlet pipe 21 and in a convenient position to be operated by the bartender.

Assuming the receptacle 11 has been positioned in the ice-filled container 10 and all of 20 the conduits, pipes, and other fittings connected thereto, and a fresh keg of beer has been opened and the beer is flowing into the receptacle 11, the bartender, by opening the pet-cock 37, allows the air trapped in the receptacle by the rising 25 beer to escape and he should not close the pet-cock until a small quantity of foam has issued therefrom, whereupon he will know that all of the air has passed out of the receptacle. The 30 gases in the beer will accumulate in the gas chamber 16 and the pressure of the gases in the chamber cannot exceed the desired pressure, since the automatic blow-off valve 35 will immediately function, in case of an excess in pressure, to bring down the pressure to the proper 35 amount. The pressure in the gas chamber should be equal to the pressure in the keg with the result that when the beer has reached approximately the level indicated in the drawings the flow of incoming beer will cease until there 40 is a withdrawal of beer from the receptacle.

When either one, or both of the taps 26, are 45 opened the beer will flow through the outlet conduits 24 from the tube 27 and the receptacle 11 and will contain the proper amount of gas, since 50 the gases compressed in the gas chamber 16 will pass through the tube 27 and entrain with the outgoing beer. The beer withdrawn from the receptacle 11 will never be flat beer, because of the mixture therewith of the gases, as just referred to. In fact, the beer may stand in the 55 container indefinitely, so long as the proper pressure is maintained on the beer in the supply keg and when withdrawn will not be flat.

Likewise, the apparatus just described eliminates the withdrawal and waste of "wild" beer, 55 as often occurs with the ordinary apparatus when a new keg of beer has just been tapped. This elimination of "wild" beer is obtained through the use of the pet-cock 37 and the automatic 60 blow-off valve 35, since by these means the pressure in the receptacle can be quickly brought to the desired level, while the compression of the gases in the chamber 16, as previously mentioned, will immediately reduce and eliminate the foam 65 on the "wild" beer that has flowed into the receptacle. The disk 27^b also acts to reduce the foam on the "wild" beer and to provide liquid 70 beer in the receptacle free from foam.

When it is desired to clean the receptacle 11 70 the fittings connecting the conduits 19 and 24 are disconnected from the receptacle, as is also the pipe 36 from the pet-cock 37, after which the receptacle is removed from the container 10. The cap 12 is then removed and the pipe 33 75

pushed through the bore in the boss 22 and the tube 27 swung to disengage the end of the pipe 34 from its conical seat in the other boss 31, whereupon the tube 27 is swung back to withdraw the pipe 33 from the boss 31 and then removed from the receptacle, together with the pipe 33, the pipe 34 having been previously removed, after which the receptacle and associated parts may be readily and thoroughly cleaned in a very short space of time.

In Fig. 3 the tube 27 is shown as having its hollow spherical lower end 29 constructed somewhat differently from the construction shown in Figs. 1 and 2, in that the pipe 33^a is an integral extension of the spherical portion 29, as distinguished from the separate pipe 33 illustrated in Fig. 1. The other pipe 34^a has a conical end seating in a conical portion of the bore through the single boss 31^b, while the opposite end of the pipe 34^a is straight and is connected to the outlet conduit similar to the outlet pipe 33 in the first mentioned form.

In the form of the invention shown in Figs. 4 and 5 there is illustrated, in place of the container 10, an electrical refrigerating unit in which the beer receptacle is positioned. This unit may comprise a suitable base 38 from which extends upwardly in circumferentially spaced relation posts 39 which support the coils 40. The receptacle 41 in this form of the invention is not arranged at an angle during use, but has its lower base portion 42 seated upon the base 38 of the refrigerating unit. The receptacle 41, however, has a portion 43 of its side wall upwardly and outwardly inclined, which causes the container to increase in cross-sectional area from its lower end toward its upper end, as clearly illustrated in the drawings.

The inlet pipe 21 is located adjacent the upper end of the upwardly and outwardly inclined wall portion 43 of the receptacle with the result that the incoming beer will flow down along such inclined wall portion and the same effect will be produced as though the container were tilted. The upper end of the container, at a point remote from the inlet and above the latter, is provided with an upward extension 44 forming a gas chamber and into which extends the flared funnel-like end 28^a of the tube 27^a. An opening is provided in the side wall of the extension 44 and such opening has fitted thereto a suitable blow-off valve 35^a. In an opening formed in the top wall of the extension 44 a pet-cock may be directly secured, or the pipe 36 leading to the remote pet-cock 37 may be secured thereto.

The operation, cleansing, and other functions of the apparatus disclosed in Figs. 4 and 5 are identical with those of the apparatus shown in Fig. 1 and, therefore, further reference thereto herein is not necessary. It should be noted that the receptacle 41 could be used in the container 10, as well as that the receptacle 11 could be used with the refrigerating unit shown in Fig. 4.

The beers put out by different breweries have different characteristics, particularly with respect to "wildness". Some beers are always very gaseous and "wild", while other beers are not so gaseous and are mild, as distinguished from "wild".

Where a very "wild" beer is being served it is desirable to reduce the passage through the tube 27 so that the beer withdrawn from the receptacle will not receive the full effect of the gas confined in the gas chamber. Of course, the amount of reduction of the passage required will be differ-

ent for various beers. In the case of some beers no reduction will be necessary, while with other beers very substantial reductions will be in order.

As illustrative of one way in which the reduction of the passage through the tube may be accomplished, I propose to employ a number of plugs which will fit in the upper end of the tube and which have passages extending through them of various sizes. These plugs may be formed of any suitable material that will not affect the taste of the beer and can be readily inserted in and removed from the upper end of the tube.

In Fig. 6 of the drawings one of these plugs 45 is illustrated in detail while in Fig. 4 the plug is shown in position in the tube, it being understood that the plug could be arranged also in the tube shown in Fig. 1.

The plug 45 has a stem which will have a tight fit in the tube and a head which will be located in the flared end 28^a of the tube to facilitate the insertion and removal of the plug. A passage 46 of the desired size extends through the plug.

Preferably all of the fittings used to connect the various pipes and valves to the receptacle are formed of bakelite or other insulating material to avoid electrolysis with a resultant undesirable taste in the beer.

Although several preferred embodiments of the invention have been illustrated and described herein, it should be understood that the invention is not to be limited thereto, except in so far as it is limited by the appended claims.

Having thus described my invention, I claim:

1. A beer cooler comprising a receptacle having a portion at its upper end providing a gas chamber, a beer inlet pipe below said portion but adjacent to the upper end of the receptacle and shaped to direct the beer against the wall of the receptacle, a beer outlet pipe adjacent the bottom of the receptacle, and a tube connected with said outlet pipe below the level of the beer inlet and extending into said gas chamber.

2. A beer cooler comprising a receptacle having a side wall inclined with respect to the vertical during use and being provided at its upper end with a portion forming a gas chamber, a beer inlet pipe below said portion but adjacent to the upper end of the receptacle and shaped to direct the incoming beer against said inclined wall, a beer outlet pipe adjacent the lower end of the receptacle, and a tube extending from said gas chamber and communicatively connected with said outlet pipe within the receptacle.

3. A beer cooler comprising a receptacle having a portion at its upper end forming a gas chamber, a beer inlet pipe below said portion, a tube having its upper end extending into said gas chamber and its lower end provided with an enlarged hollow portion having an opening thereto in communication with the interior of the receptacle, and a beer outlet pipe connected to and in communication with the enlarged hollow portion of said tube.

4. A beer cooler comprising a receptacle having a portion at its upper end forming a gas chamber and provided with a side wall inclined with respect to the vertical during use of the receptacle, a beer inlet pipe extending into the receptacle below said gas chamber and shaped to direct the incoming beer against said inclined wall, a tube in said receptacle having its upper end extending into said gas chamber and provided at its lower end adjacent the bottom of the receptacle with an enlarged hollow por-

tion having an opening therein, and a beer outlet pipe connected to said hollow portion and in communication therewith.

5. A beer cooler comprising a receptacle adapted to be arranged at an angle to the vertical during use and provided at its upper end with a laterally extending portion forming an enlarged gas chamber, a beer inlet pipe below said gas chamber and shaped to direct beer against the lower inclined wall of the receptacle, means for venting said gas chamber, a beer outlet pipe adjacent the lower end of the receptacle, and a tube having its upper end in communication with the gas chamber and its lower end in communication with said outlet pipe and said receptacle.

15. 6. A beer dispensing apparatus comprising, in combination, a coolant container, a receptacle for the beer arranged in said container, a support in said container for supporting said receptacle at an angle inclined to the vertical, said receptacle having at its upper end a gas chamber and a beer inlet pipe below said chamber, means for venting said chamber extending to a point exteriorly of the container, a beer outlet pipe connected to said receptacle adjacent its lower end and extending to a point exteriorly of the container and below said inlet pipe, and a tube within said receptacle having its upper end in communication with said gas chamber and its lower end in communication with said outlet pipe and said receptacle.

20. 7. A beer dispensing apparatus comprising, in combination, a cooling unit for the beer, a receptacle arranged within said unit and having a portion forming a gas chamber at its upper end, a beer inlet pipe below said portion, means for venting said gas chamber controlled from exteriorly of the unit, a beer outlet pipe connected to said receptacle adjacent its lower end and extending to a point exteriorly of the unit and below the inlet pipe, and a tube within said receptacle having its upper end located in said gas chamber and its lower end connected to said outlet pipe and in communication therewith and with said receptacle.

25. 8. A beer cooler comprising a receptacle having a portion of its side wall inclined with respect to the vertical and its upper end provided with a portion forming a gas chamber, a beer inlet pipe carried by said inclined wall below said gas chamber and shaped to direct the beer against said wall, a beer outlet pipe connected to the receptacle adjacent its lower end, and a tube in said receptacle having its upper end located in said gas chamber and its lower end connected to said outlet pipe and in communication therewith and with said receptacle.

30. 9. A beer cooler comprising a receptacle having a portion at its upper end forming a gas chamber, a beer inlet pipe below said portion, a tube extending from said gas chamber to adjacent the lower end of the receptacle, a disk on said tube adjacent to but below said gas chamber, and a beer outlet pipe in communication with said receptacle and the lower end of said tube.

35. 10. A beer cooler comprising a receptacle having a portion of its side wall inclined with respect to the vertical and its upper end provided with an extended portion forming a gas chamber, a beer inlet pipe carried by the receptacle below said gas chamber and shaped to direct the beer against said inclined wall, a beer outlet pipe connected to the receptacle adjacent its lower end, a tube in said receptacle having its upper end located in said gas chamber and its lower end connected to said outlet pipe and in communication therewith and with said receptacle, and a disk arranged on said tube below but adjacent to its upper end.

40. 11. A beer cooler comprising a receptacle having a portion at its upper end providing a gas chamber, a beer inlet pipe below said portion, a beer outlet pipe adjacent the bottom of the receptacle, a tube connected with said outlet pipe below the level of the beer inlet and extending into said gas chamber, and a plug arranged in said tube and having a passage extending through it.

AUGUST L. VOIGHT. 45
